(Cl. D34—13)

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 13.

FIG. 14.

FIG. 15.

FIG. 16.

FIG. 17.

FIGURES 1 through 17, inclusive, are top plan views of a set of playing cards, showing our new design.

The backs of the playing cards are conventional.

The dominant features of our design reside in the portions shown in full lines.

We claim:

The ornamental design for a set of playing cards, as shown and described.
